(57) **CLAIM**

The ornamental design for pacifier for teething, as shown and described.

DESCRIPTION

FIG. 1 is a top plan view of a pacifier for teething showing my new design;

FIG. 2 is a front elevational view thereof;

FIG. 3 is a bottom plan view thereof;

FIG. 4 is a back view thereof;

FIG. 5 is a left side elevational view thereof; and,

FIG. 6 is a back isometric view showing my design.

1 Claim, 2 Drawing Sheets

FIG-1.

FIG-2.

FIG-3.
